COUPLING FOR HIGH FREQUENCY CIRCUITS

Erich Zepler, Berlin, Germany, assignor to Telefunken Gesellschaft für Drahtlose Telegraphie m. b. H., Berlin, Germany, a corporation of Germany

Application September 20, 1930, Serial No. 483,247
In Germany October 5, 1929

6 Claims. (Cl. 250—20)

It happens quite often in the reception of radio waves that the place or point where the receiver must be mounted, is unserviceable for the mounting of an antenna, the reasons underlying the adoption of such a scheme residing, for example, in strong local disturbances or in that the receiving place is markedly screened from incoming waves by high buildings in the vicinity, while affording little protection from atmospherics, for instance.

In cases like that, various ways and means are known to alleviate the trouble; for example, the antenna and the receiver may be installed at some distance from the receiving rooms the receiver may be designed for remote control, while the audio frequency or modulation energy delivered by the last stage is transmitted to a translating or relaying device.

If the disturbances are confined to the immediate neighborhood of the receiving room, as is often true in the case of trouble due to machines, neighboring sending antennae, etc., then it is frequently sufficient to mount the receiving antenna at a distance of, say, 100 meters from the receiving room. In order to preclude all chances of disturbances the connection between antenna and receiver should consist, mainly, of a cable having a grounded metallic sheath. Inasmuch as the feed line contained inside the cable presents a very high capacity to ground, such an arrangement ordinarily is attended with a considerable attenuation in volume owing to the harmful capacitive shunt thus created.

In the accompanying drawing, in connection with which my invention is more fully described,

Figures 1 and 2 illustrate antenna lead-in structures, attenuating transferred energy, and

Figures 3 to 6 inclusive are illustrative of the present invention directed towards the elimination of capacity attenuation of lead-in conductors.

In the scheme shown in Figure 1 which represents the normal case of capacitive coupling from a high frequency circuit usually the antenna to high frequency apparatus through a condenser 2, the attenuation is given by the ratio

$$\frac{\text{Antenna capacity}}{\text{Antenna capacity} + \text{cable capacity}}$$

Referring to the drawing, A denotes the antenna, E the receiver, and K the feed or transmission cable having a grounded metallic sheath S.

The situation is similar in case of inductive coupling (Figure 2), wherein energy is trans-

ferred through a transformer 4 between high frequency apparatus and an antenna.

In what follows a circuit scheme is disclosed whereby it is feasible to preclude any harmful attenuation or reduction in volume due to the cable.

According to the invention, an inductance is inserted between the cable line and the ground, the same being so proportioned that it will tune the cable circuit exactly or roughly to the incoming wave. In this manner volumes are obtained of the same order of magnitude as in the case of direct antenna reception.

So far as the operation of this scheme is concerned, it is immaterial at what particular point along the cable the inductance is added, though for practical reasons it will mostly have to be disposed at a point where the cable is connected with the receiver.

The cable circuit tuning inductance 6 may be connected either directly with the grid of the input tube (Figure 3); or else a more favorable receiving volume may be assured by the interposition of a second tuning circuit 8 (Figure 4) and suitably chosen coupling (transformer principle), as shown in Figures 4 and 5 either inductive as shown in Figure 4 or inductive and capacitive as shown in Figure 5. For tuning the cable circuit, either a fixed or a variable inductance will have to be employed according to whether one fixed wave length or different waves are to be received. If a variable inductance is employed, the same may be either a variometer or else it may be varied in steps. Owing to the fact that the damping of cables is mostly considerable, wave steps of 5% will mostly be sufficient. In an arrangement of this kind, a unicontrol change-over switch or link mechanism 10 adapted to change the tuning of the cable or antenna coupling circuit automatically together with the tuning of the receiver is most convenient.

If several receivers are to be connected with the same antenna, then a scheme as illustrated in Figure 5 may be employed. The same requires as many cables as there are receivers. The capacity provided in this case between antenna and cable should then be chosen so that inter-action between the various receivers will be diminished to a reasonable amount. An arrangement of this sort is illustrated in Figure 6 wherein several receivers are shown individually connected by cables K to a single antenna A.

Having thus described my invention, what I claim is:

1. In combination, a high frequency circuit, a

- tunable circuit, a cable transmission line for coupling the circuits together, a variable inductor coupled between the line and ground for eliminating the effects of the distributed capacity thereof and unicontrol means for varying the tuning of the tunable circuit and the inductance of the inductor. 80
2. In combination, an antenna, a tunable circuit, a shielded transmission line for coupling the circuits together, a variable inductor coupled between the line and ground for eliminating the effects of the distributed capacity thereof and unicontrol means for varying the tuning of the tunable circuit and the inductance of the inductor. 85
- 15 3. In a signal receiving system, a receiver comprising an electron discharge device having a control electrode, an antenna, a linear feed line extending between and directly connected to said antenna and the control electrode of said electron discharge device, a shield for said line, and a supplemental tunable inductance one side of which is directly connected to said line and the other side of which is at substantially the same potential as said shield for eliminating the effects 90 of the distributed capacity thereof.
- 20 4. A radio receiving system having, in combination, an antenna, a receiver possessing at least 95
- 25

one tuned circuit, a line extending between said antenna and said receiver, a shield around said line and connected to ground, a tunable inductance connected between said line and ground for compensating for the distributed capacity between said line and said grounded shield, and uni-control means for simultaneously varying said inductance and said tuned circuit of said receiver.

5. A radio receiving system comprising a single antenna, a plurality of remote receivers, lines individually connecting each receiver with said antenna, shields around said lines, and individual tunable inductors connected to each of said lines and to ground for eliminating the effects of the distributed capacity of said lines, and uni-control means at each receiver for simultaneously varying the tuning inductor and its associated receiver. 90

6. A radio receiving system having, in combination, an antenna, a receiver possessing at least one tuned circuit, a line extending between said antenna and said receiver, a shield around said line, a tunable inductance directly connected to said line and effectively connected to said shield for compensating for the distributed capacity between said line and shield. 100
